UNITED STATES PATENT OFFICE.

HENRI JEAN JOSEPH MARIE DE REGNAULD DE BELLESCIZE, OF TOULON, FRANCE.

ATMOSPHERIC-DISTURBANCE-REDUCING MEANS.

Application filed November 3, 1922. Serial No. 598,739.

To all whom it may concern:

Be it known that I, HENRI JEAN JOSEPH MARIE DE REGNAULD DE BELLESCIZE, a citizen of the Republic of France, and a resident of 5 24 Rue Victor Clappier, Toulon, Var, France, have invented new and useful Improvements in Atmospheric-Disturbance-Reducing Means (for which I have filed an application in France, October 11, 1921), of 10 which the following is a specification accompanied by drawings.

In wireless telegraphy sometimes amplitude limiting arrangements are used for preventing the current received by the telephone or the registering apparatus from exceeding a certain maximum limit, no matter what the intensity of the oscillation generated by the receiver. Arrangements answering this description may, e. g., be 15 composed of a three-electrode tube, or two tubes connected in series. The output circuit of the limiting apparatus can supply only a limited current variation J_m (Fig. 1), and the arrangement is so provided that, 20 almost the totality mn of this variation is obtained by the potential difference Mn that the signal generates between the incoming terminals of the limiting apparatus.

These arrangements are sufficiently efficient for short waves and low-speed operation. However, if the wave length or the operating speed is increased, such arrangements cannot serve to eliminate trouble 30 caused by strong disturbances. As a matter of fact, such disturbances generate in the resonator free oscillations of great initial amplitude the duration of which may exceed that of a point or interval between two consecutive signals.

40 In accordance with the present invention, this drawback is remedied by controlling the effective resistance and the individual frequency of the resonator subjected to such disturbances, by means of an electromotive force of reaction derived from the amplitude 45 limiting apparatus. Reactions in receiving apparatus comprising three-electrode tubes are of common usage, but they have not as yet been derived from an element (e. g., tube or group of tubes) which has the special function of limiter. This arrangement is 50 new and so are the manipulating means of

which use is made of this arrangement. The arrangement may be used to good advantage for eliminating atmospherics. 55

The invention will be more clearly understood with the aid of the following description and the enclosed drawings:

Fig. 1 is a curve representing the functioning of the limiting device. 60

Fig. 2 exemplifies but does not limit one embodiment of the invention in a receiving apparatus.

Fig. 3 is a curve of a current caused by a disturbance at the output side of the limiting device. 65

Fig. 4 is a curve of the potential of the reaction on the resonator caused by the said current.

In Fig. 2 it is assumed that the resonator 70 1—2—3 is simultaneously actuated by a signal and an aperiodic disturbance. It may be, e. g., an antenna comprising a self-induction 1, a tuning condenser 2, and an ohmic resistance 3. This resonator actuates 75 an amplifier shown at 5 and then an amplitude limiting device illustrated at 7. The current j of this limiting device has a characteristic of the form shown in Fig. 1. The receiving arrangement comprises the usual 80 elements, e. g., a resonator 9 tuned to the frequency of the signal, a detector 10, a registering galvanometer 11. Furthermore the following means are provided for controlling the adjustment of the apparatus: 85

Adjusting to the limit value MN of the potential difference caused by the signal at the terminals of the limiter 7. This result may, for instance, be obtained by means of the switch 6 which changes the primary of 90 the transformer 14 in a manner to vary the amplification.

Adjusting, distinct from the above, of the electromotive force of reaction exercised by the limiter on the resonator 1—2. This 95 adjusting is effected, e. g., by affecting in a suitable manner the mutual induction coefficient between a coil 13 forming part of the resonator and a coil 12 traversed by a part i of the plate current j , the coils 12 100 and 13 constituting the primary and secondary coils of a variable coupling arrangement 4.

Adjusting of the phase of current i . This

phase may be varied by almost 180° under the control of the condenser 8. Furthermore, the coil 12 may be reversed in a manner to change the sign of the mutual inductance 4 which is equal to a dephasing of π .

Notwithstanding the fact that the invention is independent of the theory by means of which it may be explained, the functioning of the apparatus may be set forth in the following manner to give the best method of utilization and adjusting. R, L, C are, respectively, the resistance, the self-induction and the capacity of the resonator 1—2, δ_o its logarithmic decrement;

$$\omega_o = \frac{1}{\sqrt{LC}}$$

its natural frequency, $e = E \sin (\omega_o t - \alpha)$ the electromotive force exercised by the pulsating signal ω_s , $v = V \sin \omega_s t$ the potential difference developed in the resonator 1—2 and exercised by it on the receiver. f is the electromotive force of reaction generated in the coil 13 by coil 12 traversed by current i .

The oscillation in the resonator 1—2 is governed by the equation

$$e + f = RC \frac{dv}{dt} + LC \frac{d^2v}{dt^2} + v \quad (1) \quad 30$$

As long as the voltage exercised on the limiter does not exceed the value MN (Fig. 1), i. e., for all the oscillations the amplitude of which does not exceed that of the signal, the limiter 7 operates in a rectilinear part of its characteristic, whereby the currents i and j remain always proportional to the potential difference v . The electromotive force of reaction has, therefore, the expression

$$f = K_s V \sin (\omega_s t + \psi)$$

K_s is a constant coefficient as long as none of the elements of the receiver are modified. ψ is a phase which may be adjusted by means of condenser 8.

Let us transpose this expression of f in the equation 1. We will find that the amplitude V of the oscillation developed by the signal in the resonator is:

$$V = \frac{E}{\sqrt{\left[1 - \left(\frac{\omega_s}{\omega_o}\right)^2 - K_s \cos \psi\right]^2 + \left[\frac{\delta_o \omega_s}{\pi \omega_o} - K_s \sin \psi\right]^2}}$$

In order that the signal attain its greatest possible intensity, we must annul the expression

$$1 - \left(\frac{\omega_s}{\omega_o}\right)^2 - K_s \cos \psi$$

and we must render very weak the expression

$$\frac{\delta_o \omega_s}{\pi \omega_o} - K_s \sin \psi.$$

Since ψ being assumed to be positive, (suitable sign of the mutual inductance 4); the above mentioned double condition is realized by manipulating the pulsation ω_o by means of the variable condenser 2, and the reaction K_s by tightening or loosening the coupling between the coils 13 and 12. The result obtained is the better, the sharper the tuning of the condenser 2. As a result of this, if the amplitude MM of the oscillation at the terminals of the limiting apparatus 7 is insufficient,—this will be noticed for instance by the deviation of the galvanometer 11—the amplification is increased by means of the switch 6 and the tuning of ω_o , and K_s is again attempted in the above described manner. Summing up, when the signal is to be received the resonator 1—2 possesses an individual pulsation ω_o different from that of the signal and given by

$$\omega_o = \frac{\omega_s}{\sqrt{1 - K_s \cos \psi}}, \quad 85$$

the over-tension V/E is equal to

$$\frac{1}{\frac{\delta_o \omega_s}{\pi \omega_o} - K_s \sin \psi} \quad 90$$

or practically

$$\frac{\pi}{\delta_o - K_s \sin \psi} \quad 95$$

it is stronger than if there were no reaction. Finally, the limiting apparatus is subject to an oscillation having an amplitude which is slightly inferior to that corresponding to the saturation.

The free oscillation created in the resonator 1—2 by a strong disturbance is damped under the conditions illustrated in Figs. 3 and 4. Instead of attaining the amplitudes Aa , Bb , which would be the case if the saturation effect did not exist, the variation of the output current of the limiting apparatus does not exceed the amplitude J_m permissible by the characteristics. As a result of this, instead of affecting the damped sine form indicated on the dotted line, the electro-motive force of reaction proportional to

$$\frac{dj}{dt} \quad 115$$

takes the irregular form indicated in full line (Fig. 4). This will be the case until time θ for which the amplitude of the oscil-

lating train does not exceed that of the signal.

The phenomena following the instant θ may be neglected, because a freely damped oscillation having initial amplitude equal to that of the signal is rapidly extinguished. We have left therefore the time from 0 to θ . The reaction is no more of sine form, and can therefore not be represented by an expression of the form $KV \sin(\omega t + \psi)$. However, an examination of Fig. 4 will show that the reaction is reduced in proportion to the intensity of the train, whereby the components $K_s \cos \psi$ and $K_s \sin \psi$ are replaced by others X and Y of lower amplitude:

$$X < K_s \cos \psi \quad Y < K_s \sin \psi$$

The pulsation W_z of the free oscillation must also at all times satisfy the equation

$$\left(\frac{\omega_x}{\omega_0}\right)^2 = 1 - X$$

Just in the instant θ it will have a variable value, which is different from ω_s of the signal, and nearer to that of ω_0 individual to the resonator.

Furthermore, the damping proportional to

$$\left(\frac{\delta_0 \omega_s}{\pi \omega_0} - Y\right)$$

is increased.

In other words, the dangerous part of the oscillating train is rapidly damped, and this happens on a frequency different from that of the signal. The disturbance can not, therefore, disturb the following circuits, which are tuned either to the frequency of the signal (for instance, the resonator as of Fig. 2) or to the frequency of the modulation resulting from the interference between the signal and a local sending.

The operating condition is the better the higher the resistance (3—Fig. 2) individual to the resonator, and the more the advance ψ of the electro-motive force of reaction differs from 90° with respect to the potential difference. If the angle ψ were equal to 90° (this would be obtained if condenser 8 were eliminated from Fig. 2) the improvement relative to the damping would subsist, but not those relative to the frequency difference between the free oscillation and the signal.

Circuit arrangements like the one shown in Fig. 2 may be constructed for resonators located after the detector and tuned to the modulation frequency of the signal. It is not necessary that the circuits placed between the resonator subjected to the reaction and the limiting apparatus be aperiodic; the receiving may in the usual manner be effected by means of a plurality of resona-

tors in series either ahead of the amplifier or inside of this apparatus. Obviously, the result would not be modified if the reaction were obtained from a circuit subsequent to the limiting apparatus.

It should be understood that the invention is not limited to the exemplification herein disclosed, but may be varied in numerous ways in which the essential constituting elements are combined. The apparatus, such as the amplifiers, limiters, detectors, etc. may be a suitable type, the purpose of these being merely to fulfill the above described functions.

Having described my invention I declare that what I claim is—

1. In radio receiving apparatus, the combination of a resonant circuit, an amplifier operatively associated with said circuit, a current limiting device, associated with said amplifier, detecting and indicating apparatus, and means for impressing on said resonant circuit an E M F derived from said current limiting device.

2. In radio receiving apparatus for discriminating against atmospheric disturbances, the combination of a resonant circuit having a natural frequency different from that of the signal desired, an amplifier connected to said circuit, a current-limiting relay connected to said amplifier and means for impressing upon said resonant circuit an electromotive force derived from said limiting relay.

3. In radio receiving apparatus for discriminating against atmospheric disturbances, the combination of a resonant circuit having a natural frequency different from that of the signal desired, an amplifier connected to said circuit, a current-limiting relay connected to said amplifier, means for impressing upon said resonant circuit an electromotive force derived from said current-limiting relay, and means for controlling the phase-relation of the electromotive force supplied to said resonant circuit.

4. In radio receiving apparatus for discriminating against atmospheric disturbances, the combination of a resonant circuit having a natural frequency different from that of the signal desired, an amplifier connected to said circuit, a current-limiting relay connected to said amplifier, means for impressing upon said resonant circuit an electromotive force derived from said current-limiting relay and means for causing the electromotive force so impressed to oppose the flow of currents having a frequency equal to the natural frequency of said circuit.
